Fig. 1

Fig. 2

Fig. 3

FIG. 1 is a perspective view of a playground climber, embodying my new design;

FIG. 2 is a top plan view thereof; and

FIG. 3 is a front elevational view thereof.

The characterizing feature of the design resides in a ladder arrangement extending the height of the playground climber at each apex.

I claim:

The ornamental design for a playground climber, substantially as shown and described.
